(57) **CLAIM**

The ornamental design for a clip, as shown and described.

DESCRIPTION

FIG. 1 is a perspective view of a clip in accordance with the new design;

FIG. 2 is a front view thereof;

FIG. 3 is an enlarged view of a first end of the clip as viewed in FIG. 2;

FIG. 4 is a back view thereof;

FIG. 5 is a right side view thereof;

FIG. 6 is a left side view thereof;

FIG. 7 is a top view thereof;

FIG. 8 is bottom view thereof; and,

FIG. 9 is a cross-section view of the first end of the clip as viewed in FIG. 8.

The broken lines shown represent unclaimed subject matter and form no part of the claimed design.
